Primary Examiner — Elizabeth J Oswecki(74) *Attorney, Agent, or Firm* — Finnegan, Henderson, Farabow, Garrett & Dunner, LLP(57) **CLAIM**

The ornamental design for a kiosk, as shown and described.

DESCRIPTION

FIG. 1 is a front left perspective view of a kiosk showing our new design;

FIG. 2 is a front right top perspective view thereof;

FIG. 3 is a rear left top perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines shown in the drawings represent portions of the kiosk that form no part of the claimed design.

1 Claim, 9 Drawing Sheets(56)
